UNITED STATES PATENT OFFICE.

ALBAN SCHMALZ, OF CHICAGO, ILLINOIS.

STOPPER FOR BOTTLES.

1,177,145.

Specification of Letters Patent. Patented Mar. 28, 1916.

Application filed May 21, 1915. Serial No. 29,457.

To all whom it may concern:

Be it known that I, ALBAN SCHMALZ, a citizen of the Republic of Brazil, residing at 1319 Belmont avenue, in the city of Chicago, 5 county of Cook, and State of Illinois, have invented certain new and useful Improvements in Stoppers for Bottles, of which the following is a specification.

My invention relates to improvements in 10 stoppers or closures for bottles and other receptacles and more particularly to stoppers of paper or other suitable material utilized to close the mouths of bottles for containing milk and other liquids.

15 The objects of my invention are to so construct the stopper that it may be easily, conveniently and quickly removed from or placed in position in the mouth of the bottle and to so arrange a part thereof that it may be moved or turned outwardly on the remainder to provide a small opening through which the contents of the bottle or a portion thereof may be poured. These and other objects I accomplish as hereinafter set forth 20 in the following description and as particularly pointed out in the appended claims, reference being had to the accompanying drawings in which a preferred adaptation or embodiment of my invention is shown.

25 In the accompanying drawings: Figure 1, is a plan view of my improved stopper or closure. Fig. 2, is an edge view of the stopper with the finger grasping projection and the door turned to their open position. Fig. 3, is a vertical section through a fragment of 30 a bottle neck and a stopper in place therein, the projection and door of the stopper being shown closed in full lines and open in dotted lines. Fig. 4, is a central vertical section 35 through the improved stopper with the door in open position, the curve of movement of the door being indicated by dotted lines. Fig. 5, is an enlarged edge elevation of the stopper with the door closed to illustrate the 40 wedge shaped form of the door. Fig. 6, is a plan view of a blank from which the stoppers are made to illustrate the manner in which the said stoppers are cut to prevent 45 waste of material.

50 In referring to the accompanying drawings in detail, like numerals designate corresponding parts.

In Fig. 3, I have shown a fragment 1, of the neck of a conventional bottle utilized as 55 a receptacle for milk or other liquids which is provided with an interior annular groove

2, in which the stopper or closure is adapted to be fitted.

My improved stopper or closure as shown 60 comprises a flat disk 3 of paper or other suitable material which is of circular form except at the point where a finger grasping 65 and lifting projection 4, is formed. This projection is integral with the disk and is preferably formed from the small nearly 70 triangular portion of material 5, located in the blank between the peripheries of the disks to be cut therefrom as shown in Fig. 6. The two side edges of the projection curve in a direction oppositely to the circumferential 75 curve of the disk and merge in said circumferential curve substantially as shown in Fig. 1. The projection 4, is adapted to be turned up at its inner extremity on the curve of the disk as indicated by the dotted line 6, in Fig. 1, so as to assume approximately the 80 position shown in full lines in Fig. 3, when in place in the mouth of a bottle.

To permit the removal of the contents of the bottle or a portion thereof without removing the stopper or closure, I provide a 85 door 7 which is integral with the disk 3 and is formed by cutting two slits 8 in the body of said disk which extend inwardly and preferably diametrically, see Fig. 1. As shown the door is approximately in the form of a segment of the disk, and its side edges and the corresponding side edges of the slit in the disk are preferably formed on a slight slant so that the door when closed 90 will wedge into place substantially as indicated in Fig. 5. The projection 4 is preferably extended from the door portion of the disk 3, so that a short pull upward on the projection will lift the door portion and 95 turn it to the position shown in dotted lines in Fig. 3, and full lines in Fig. 4, thereby providing a small opening through which the contents or a portion of the contents of the bottle may be poured. The line upon 100 which the door turns in opening or closing is shown by the dotted line 9, in Fig. 1, and the curve of its movement is indicated by the dotted curved line 10 in Fig. 4.

The two great advantages of this invention are that the contents of the bottle may be removed without removing the stopper and an extremely convenient means is provided for opening or closing the small opening in the stopper and also removing the 105 said stopper from the bottle.

While I have illustrated and described

preferred forms of construction for carrying my invention into effect, this is capable of a wide range of variation, alteration, modification and change without departing 5 from the spirit of my invention, I therefore do not wish to be limited to the construction herein shown and described, but desire to avail myself of all such variations, alterations, modifications and changes as fairly 10 fall within the scope of the appended claims or may be construed to be within the scope thereof by involving the doctrine of equivalents.

What I claim as my invention and desire 15 to secure by Letters Patent is:

1. A device of the class described, comprising a disk having two radial slits, a segmental portion between said slits constituting a door, the portions of said disk on 20 opposite sides of said door constituting supports for said door, when closed, a triangular finger grasping projection extending from said door, the door being adapted to turn on a straight line extending between 25 the inner ends of the slits and the finger grasping projection to turn on a curved line forming a continuation of the circumferential peripheral edge of the disk, the door and finger grasping projection being integral with each other and the disk, and 30

having five sides, one of which forms the juncture with the disk, two others of which are straight and are formed by the slits, and the remaining two of which are slightly curved and constitute the exterior sides of 35 the finger grasping projection.

2. A device of the class described, comprising a circular disk having two radial slits, a door formed by the slotted segmental portion of said disk and a triangular finger 40 grasping projection extending centrally out from said door, the marginal portions on opposite sides of the slotted segmental portion constituting supports for said door when closed, and the corresponding side 45 edges of the door and marginal portions being on a slant so that the door will wedge in place when closed, the door being adapted to turn on a straight line extending between the inner ends of the slits and the projection on a curved line forming a continuation of the circumferential edge of the disk.

In testimony whereof I have hereunto affixed my name in the presence of two witnesses.

ALBAN SCHMALZ.
